UNITED STATES PATENT OFFICE.

JAMES C. STANZIONE, OF NEWBERRY, PENNSYLVANIA.

CASEMENT-WINDOW ADJUSTER.

Application filed November 13, 1928. Serial No. 319,079.

The present invention relates to improvements in closure fasteners and has for its principal object to provide a simple and efficient device for association with a swinging window whereby the same may be held secure in any open position so that rattling or accidental closing of the window will be prevented.

Another important object of the invention is to provide a closure fastener of the above mentioned character that will at all times be positive and efficient in its operation, the same being further of such construction as to permit the same to be readily and easily installed on a window without necessitating any alterations.

Still a further object is to provide a casement adjuster of the above mentioned character which is simple in construction, inexpensive, strong and durable and further well adapted to the purpose for which it is designed.

Other objects and advantages of the invention will become apparent from the following description when taken in connection with the accompanying drawings.

In the accompanying drawings wherein like reference characters indicate corresponding parts throughout the same:

30 Figure 1 is a top plan view of the casement adjuster embodying my invention showing the manner in which the same is used to secure a vertically swinging window sash in a partially opened position.

35 Figure 2 is a side elevation thereof.

Figure 3 is an enlarged fragmentary top plan view of the adjacent ends of the tubing and the slidable rods showing the spring actuated locking device associated with the 40 aforementioned parts.

Figure 4 is a view partly in elevation, and partly in section of the locking device, as applied to the tubing and the adjacent end of the slidable rod.

45 Figure 5 is an enlarged fragmentary detail sectional view showing the connection between the outer end of the tubular member and the bracket that is secured on the window sill.

50 Figure 6 is a similar view showing the con-

nection between the outer end of the rod and the bracket that is secured to the vertically swinging window sash.

Figure 7 is a detail perspective view of the bracket for attaching the tubular member to 55 the window sill.

Figure 8 is a similar view of the bracket for attaching the rod to the window sash.

Figure 9 is a perspective view of the casting forming a part of the locking device. 60

Figure 10 is a fragmentary perspective view of the tubular member forming a salient part of the present invention.

Figure 11 is a detail perspective view of the cap that is secured on the outer end of the 65 tubular member.

Figure 12 is a view similar to Figure 10 illustrating the slidable rod, and

Figure 13 is a detail perspective view of one of the levers forming a part of the lock- 70 ing device.

In the drawings wherein for the purpose of illustration is shown the preferred embodiment of my invention the numeral 1 designates generally my improved casement adjuster, the same comprising an elongated tubular member 2 that is open at its outer end. The inner end of this tubular member is formed with an inwardly directed flange 3, the purpose of which will be presently apparent. 80

Furthermore the inner end portion of the tubular member is externally threaded as illustrated at 4, with reference more particularly to Figures 4 and 10 of the drawings. 85

A cap 5 is removably fitted over the outer open end of the tubular member 2, and this cap as well as the outer end portion of the tubular member are formed with diametrically opposed registering openings to accommodate the headed pin 6.

This headed pin extends through an opening formed in the central raised portion 7 of a bracket 8, which bracket is formed with the laterally disposed apertured ears 9 for permitting the bracket to be rigidly secured to the window sill A of a window frame B in which the vertically swinging window sash C is mounted. 95

A pin 10 extends through an opening 100

formed in the lower end portion of the headed pin for disposition against the bottom face of the raised central portion 7 of the bracket 8 and this pin provides a means whereby the 5 outer end portion of the tubular member 2 is capable of swinging in a horizontal plane.

The casement adjustment further includes the provision of an elongated rod 11, the inner end portion of which is slidably disposed 10 through the flanged inner end of the tubular member 2 and a head 12 is formed on the inner end of the rod 11 for disposition within the tubular member 2, said head 12 cooperating with the flange 3 to prevent the disengagement 15 of the rod from the tubular member.

This detail is more clearly disclosed in Figure 4 of the drawings.

A bracket designated generally by the numeral 13 is formed with a pair of parallel 20 spaced laterally extending apertured lugs 14, and this bracket is rigidly secured to the inner face of the swinging window sash C adjacent the lower edge thereof. The outer end of the rod 11 is pivotally secured between the 25 laterally extending ears 14 through the medium of the pin 15 that extends through the openings formed in the outer end portions of said ears, and which pin further projects transversely through the outer end portion of 30 the rod 11, in the manner as more clearly suggested in Figure 6.

At the meeting ends of the tubular member 2 and the rod 11, there is arranged the locking devices denoted generally by the reference character 16. This locking device includes a casting 17 that is formed with an enlarged cavity 18 in the bottom thereof, the central portion of the cavity being wider than the end portions so as to form the shoulders 35 19 and 20, respectively, as more clearly shown in Figure 9, and the purpose thereof will be presently described. The top of the casting 17 is formed with a rectangular shaped opening 21 that has communication with the cavity 18. The inner end of the casting is formed 40 with a threaded bore 22 that communicates with the adjacent end of the cavity 18 and the threaded inner ends of the casting is secured on the threaded inner end of the tubular member 2, as indicated in Figure 4 whereby said 45 casting is rigidly secured on the inner end of the tubular member, and the outer end of the casting is formed with an opening 23 that is arranged in alignment with the opening 22 to permit the free sliding movement of the rod 50 11 therethrough.

A pair of plate like levers 24 and 25 extend 55 downwardly into the cavity 18 through the opening 21 formed in the top of the casting, the upper ends of these levers forming handles. The lower ends of the levers are formed with holes such as shown at 26 in Figure 13 which are slightly larger than the diameter of the rod 11, and the rod extends through 60 these holes in the lower ends of the levers.

Suitable expandible coil springs 27 encircle the rod 11 within the casting 17, and as is clearly shown in Figure 4, one of these coil springs is disposed between the outer side face of the lever 24, and the inner end of the 70 tubular member 2, while the other end of the coil spring is disposed between the outer side face of the complementary lever 25, and the adjacent end of the casting. These springs normally hold the lower ends of the levers 75 away from the shoulders 19 and 20, respectively, so as to dispose the levers at an angle whereby to afford a clamping action of the sides of the hole through the levers 24 and 25 against the rod 11 when under the influence 80 of the coil springs 27, and when the parts are arranged in this position, the rod 11 cannot move with respect to the tubular member 2, thus the window sash C may be locked in any open adjusted position.

Whenever it is desired to swing the window sash, the operator grasps the outer or upper ends of the levers 24 and 25, and pushes said levers toward each other so that the same assumes a vertical position and whereby the 90 lower ends of the levers will abut against the shoulders 19 and 20, thus permitting the free movement of the rod 11 through the holes 26.

In this way, the vertically swinging window sash may be secured in any open adjusted position against rattling and further 95 against being accidentally shut.

The simplicity of my improved casement adjuster enables the same to be readily and easily installed, and the device will at all 100 times be positive and efficient in carrying out the purposes for which it is designed.

While I have shown the preferred embodiment of my invention it is to be understood that minor changes in the size, shape and arrangement of parts may be resorted to without departing from the spirit of the invention, and the scope of the appended claims.

Having thus described the invention, what I claim as new and desire to secure by Letters 110 Patent is:

1. In a window fastener, a tubular member having its inner end formed with an inwardly directed flange, means for pivotally securing the outer end of the tubular member to a window casing, a rod pivotally secured at its outer end to a swinging window mounted in the casing, the inner end of the rod being slidably within the inner end of the tubular member, a head formed on the inner end of the rod for engagement with the flange to prevent the displacement of the rod from the tubular member, a locking device associated with the adjacent end of the tubular member and the slidable rod for securing the window in open position of adjustment, said locking device including a casing secured at one end on the inner end of the tubular member, the other end of the casing being formed with an opening through which said rod is slidable, 130

the top of the casing being formed with an opening, a pair of opposed levers extending downwardly through the opening in the top of the casing, the lower ends of the levers being formed with registering openings of a diameter slightly greater than that of the rod and through which said rod is disposed, and coil springs encircling the rod and disposed between the outer side faces of the lower end portions of the levers and the adjacent ends of the casing for normally holding said levers in a canted position to cause a clamping action on the rod and prevent casual sliding movement thereof.

15 2. In a window fastener, a tubular member having its inner end formed with an inwardly directed flange, means for pivotally securing the outer end of the tubular member to a window casing, a rod pivotally secured at its outer end to a swinging window mounted in the casing, the inner end of the rod being slidable within the inner end of the tubular member, a head formed on the inner end of the rod for engagement with the flange to prevent the displacement of the rod from the tubular member, a locking device associated with the adjacent end of the tubular member and the slidable rod for securing the window in open position of adjustment, said locking device including a casing secured at one end on the inner end of the tubular member, the other end of the casing being formed with an opening through which said rod is slidable, the top of the casing being formed with an opening, a pair of opposed levers extending downwardly through the opening in the top of the casing, the lower ends of the levers being formed with registering openings of a diameter slightly greater than that of the rod and through which said rod is disposed, and coil springs encircling the rod and disposed between the outer side faces of the lower end portions of the levers and the adjacent ends of the casing for normally holding said levers in a canted position to cause a clamping action on the rod and prevent casual sliding movement thereof, and stop forming members arranged within the casing at predetermined points for cooperation with the lower ends of the levers whereby the rod can be free to slide through the casing when the levers are disposed against the shoulders.

In testimony whereof I affix my signature.
JAMES C. STANZIONE.
